TOY BALLOON TIRE WHEEL

Frank J. Merz, Jr., and Clayton B. Merry,
Seattle, Wash.

Application June 1, 1934, Serial No. 728,530

4 Claims. (Cl. 46—48)

Our invention relates to toy balloon tire wheels and construction methods, and certain objects of the invention are to provide, as an article of manufacture, a toy balloon tire wheel that is extremely light in weight and which is particularly adapted for use on model and toy airplanes. Further objects are to provide a novel and inexpensive method for constructing toy balloon tire wheels.

With the above and other objects in view which will appear as the description proceeds, the invention consists of the novel construction, adaptation, combination, arrangement and method hereinafter described and claimed. These objects are accomplished by devices illustrated in the accompanying drawing; wherein: Figure 1 is a group view in central vertical section showing the different elements arranged in their relative positions for the first step in the assemblage of the tire wheel; Fig. 2 is a corresponding view showing the second step in the method of assembling the wheel; Fig. 3 is a corresponding view showing the third and final step in the assemblage of the wheel; and Fig. 4 is a view in side elevation of the completed tire wheel.

Referring in detail to the drawing, the numeral 5 designates an ordinary toy balloon that is made of thin rubber and is partly inflated. The balloon has the usual neck 6. The first steps in assembling the tire wheel consist in passing the neck 6 through a central hole 7 in a female hub member 8 to a point where the neck joins the main body of the balloon, and in coating the interior wall of the balloon, at this point, with liquid cement or other adhesive material as shown at 9 in Fig. 1 of the drawing.

The second step in the method of assembling the wheel consists in pressing the smaller end of a male hub member 10 against the central outer end portion 11 of the balloon 5 that is opposite to the neck 6 and in forcing said portion inwardly and through the hole 7 in the female hub member 8 and into the neck 6 where said portion contacts with the adhesive material 9 and is thereby cemented all around to the inside of the neck as clearly shown in Fig. 2. In this operation, the male hub member 10 is jammed tightly into the female hub member 8 where it remains fixed, and the body portion of the balloon 5 is converted into an annular pneumatic airtight tire 12.

In the third step of the method, the outer end of the portion 11 of the balloon which projects through the hole 7 in the female hub member 8, together with the neck 6, is trimmed off flush with the coinciding ends of the male and female hub members 8 and 10. A thin hub cap 13 is then cemented or glued to said coinciding or flush hub ends. A small hole 14 extends centrally through the male hub member and cap for use in installing the wheel on the thin axle of a model

or toy airplane as will be understood. Adhesive material may also be used on outside portions of the balloon 5 for securing the male and female hub members in place if desired.

The hub members 8 and 10 and the hub cap 13 may be made of balsam or other light wood, or they may be made of thin hollow aluminum or other material of very light weight. The thin toy balloon, also being of exceedingly light weight, makes the entire device extremely light and particularly adapted for use on model and toy airplanes. The method of assembling or constructing the wheels is quite simple and comparatively inexpensive, and provides a pneumatic toy wheel and tire that is airtight, durable and serviceable for use on model and toy airplanes.

Having thus described our invention, what we claim and desire to secure by Letters Patent of the United States is:—

1. An article of manufacture comprising a partly inflated thin rubber toy balloon having a neck joined thereto, a female hub member encircling the point of joiner of the balloon and neck, the central outer end portion of the balloon opposite the neck pressed into and extended through the portion of the neck that is encircled by the female hub member, means for securing said balloon portion within said neck portion to form an air tight connection, a male hub member extended into said balloon and neck portions and extending through and flush with the end of the female hub member, said balloon and neck portions also terminating flush with the flush ends of said male and female hub members, a hub cap secured to the flush ends of said male and female hub members, and said male hub member and hub cap having a small hole extending centrally therethrough.

2. An article of manufacture comprising a partly inflated toy balloon having a short neck, a female hub member encircling the short neck, the central outer end portion of the balloon extending into the neck and secured therein to form an air tight annular tire of the balloon, and a male hub member extending into said short neck, balloon portion and female hub member.

3. As an article of manufacture, a toy balloon tire wheel comprising a partly inflated toy balloon having a short neck, the central outer end portion of the balloon extending into the neck and secured therein to form an air tight annular tire, and a hub secured through said balloon portion and neck.

4. As an article of manufacture, a toy balloon tire comprising a partly inflated toy balloon having a short neck, and the central outer end portion of the balloon extending into the neck and secured therein to form an air tight annular tire.
